DOUBLE TOILET TISSUE ROLL HOLDER

Sydney Carpenter, Long Beach, Calif., assignor of one-tenth to Gadget-Of-The-Month Club, Inc., Los Angeles, Calif., a corporation of California

Application October 13, 1955, Serial No. 38,348

Term of patent 14 years

(Cl. D4—3)

FIG. 1

FIG. 2

FIG. 3

The rolls of toilet tissue disclosed by means of broken lines are only shown for illustrative purposes.

I claim:

The ornamental design for a double toilet tissue roll holder, substantially as shown and described.
